Attorney

UNITED STATES PATENT OFFICE

JOHANN EINFALT, OF NUERMBERG, GERMANY

TOY SWIMMING ANIMAL

Application filed September 27, 1930, Serial No. 484,801, and in Germany August 6, 1930.

This invention relates to a toy swimming animal. It is known, that by a driving mechanism arranged inside the figure, a propelling movement of the legs is obtained. According to the invention, besides the propelling movement of the legs, an adjustment of the hinge-like collapsible webs fastened on the legs is obtained in the water. Further the head is also moved.

10 An embodiment of the invention is illustrated by way of example in the accompanying drawings in which:

Fig. 1 shows the toy in side elevation.

Fig. 2 is a top plan view of Fig. 1.

15 Fig. 3 shows in top plan view the webs raised.

The swimming animal, for example a duck, consists of the water-tightly united parts *a* and *b*, the part *b* carrying the driving mechanism *c* which is provided with a rotatable crank *d*. The crank *d* moves in a slot *f* of a guide bar *g*. On the front end of the guide bar *g* upwardly projecting lugs *h* are provided in which the head *i* of the swimming animal is movably mounted and held by means of a pin. Two further lugs *k* are provided on the guide bar *g* which project downwardly and have each a slot *l*, in which the crank portion of a rod *m* is guided, which is downwardly bent on the outer ends. Webs composed of the elements *n* and *o* are fastened on the ends of rod *m* and held collapsible. An abutment stop *p* with angular projection *q* for the webs is fixed on the rod *m*. This projection *q* allows only a limited collapsing of the webs.

The operation is as follows:

During the running down of the driving mechanism the crank *d* revolves in a circle, so that a reciprocating movement is imparted to the guide bar *g*. Owing to this movement the crank mounted in the lugs *k* and guided in the slots *l*, as also the rod *m* with the webs *n*, *o*, are moved backwards and forwards. The head must carry out a similar movement at the same time. As already mentioned, the webs of the swimming animal are collapsibly fixed on the rod *m*. During the forward movement of the ends of rod *m* the webs will collapse owing to the pressure

of the water, so that they do not offer any resistance. However, during the return movement they spread out so that they are pressed against the water. This arrangement is provided for the purpose of obtaining an easy propelling movement of the animal in the water.

I claim:

1. A toy swimming animal in which to the legs a rowing movement is imparted, comprising in combination with the figure of a swimming bird, a driving mechanism in this figure, a revolving crank forming part of said driving mechanism, a guide bar having a slot to which a reciprocating movement is imparted by the revolving movement of the crank, a transverse crank rod the ends of which are bent downwards, a crank on said transverse rod engaging said guide bar and oscillated by the reciprocating movement of said guide bar and webs fixed to the downwardly bent ends of said transverse rod.

2. A toy swimming element as specified in claim 1, comprising in combination with the transverse crank rod and the webs, an abutment on each bend of said crank rod in front of the corresponding web, and an angular nose on each end of said transverse rod behind the corresponding web.

3. A toy swimming element as specified in claim 1, comprising in combination with the shiftable guide rod, a head of the swimming animal hingedly connected with the front end of said shiftable guide rod so that at the reciprocating movement of said guide rod said head carries out oscillating movements.

In testimony whereof I affix my signature.

JOHANN EINFALT.
